(57) **CLAIM**

The ornamental design for a golf overshoe, as shown and described.

DESCRIPTION

FIG. 1 is a left side elevation view of a golf overshoe showing our new design;

FIG. 2 is a right side elevation view;

FIG. 3 is a front elevation view;

FIG. 4 is a rear elevation view;

FIG. 5 is a top plan view; and,

FIG. 6 is a bottom plan view of a golf overshoe showing our new design.

The broken lines of an exemplary user's ankle are for illustrative purposes only and form no part of the claimed design.
